DESIGN FOR A REFLECTOR POST

Richard Ray Robinson, Sr., Pueblo, and Granville Lannon, Denver, Colo., assignors to The Colorado Fuel and Iron Corporation, a corporation of Colorado

Application July 3, 1940, Serial No. 93,400

Term of patent 14 years

To all whom it may concern:

Be it known that we, Richard Ray Robinson, Sr., and Granville Lannon, citizens of the United States, residing, respectively, at Pueblo, Colorado, and Denver, Colorado, have invented a new, original, and ornamental Design for a Reflector Post, of which the following is a specification, reference being had to the accompanying drawing, forming part thereof.

Figure 1 is a front elevational view of the re-

flector post, showing our new design, the broken line across the lower end indicating indeterminate length.

Figure 2 is a side elevational view thereof; and Figure 3 is a plan view.

We claim:

The ornamental design for a reflector post, substantially as shown.

GRANVILLE LANNON.
